United States Patent Office

Des. 216,745
Patented Mar. 3, 1970

216,745

CANDLE

Wilfred L. Reiher, Sun City, Ariz., assignor to Candle World, a corporation of Arizona

Filed Sept. 23, 1968, Ser. No. 13,672

Term of patent 14 years

Int. Cl. D26—05

U.S. Cl. D73—1

The figure on the drawing is a perspective view of a candle showing my new design. The details and features seen in this view continue around the candle.

I claim:

The ornamental design for a candle, as shown and described.
